UNITED STATES PATENT OFFICE.

SOUTH G. PRESTON, OF CATLETTSBURG, KENTUCKY.

GUARD FOR SHAFT OR POLE ENDS.

SPECIFICATION forming part of Letters Patent No. 655,734, dated August 14, 1900.

Application filed May 21, 1900. Serial No. 17,449. (No model.)

To all whom it may concern:

Be it known that I, SOUTH G. PRESTON, a citizen of the United States of America, residing at Catlettsburg, in the county of Boyd and 5 State of Kentucky, have invented certain new and useful Improvements in Guards for Shaft or Pole Ends, of which the following is a specification, reference being had therein to the accompanying drawings.

10 This invention relates to safety devices for pole and shaft ends.

The object of the invention is to provide a guard or fender to be applied to the shafts' ends in order to remove the element of danger incident to its contacting with man or beast. Many instances are known where the 15 ends of shafts have penetrated men and horses or otherwise injured them; and it is the object of this invention to provide a cushioned 20 tip to be applied to the end of the shaft to act as a guard.

Furthermore, the object of the invention is to produce a padded tip which may be readily removed and applied, said tip being provided 25 with securing means whereby it is held against accidental displacement.

Finally, the object of the invention is to provide a protecting-tip which will prove efficient and satisfactory in use and which is 30 strong, durable, and comparatively inexpensive.

With the above and other objects in view the invention consists in the details of construction and in the arrangement and combination of parts to be hereinafter more fully 35 set forth and claimed.

In describing the invention in detail reference will be had to the accompanying drawings, forming part of this specification, where- 40 in like characters denote corresponding parts in the several views, and in which—

Figure 1 is a view in elevation of a portion of a shaft with the invention applied. Fig. 2 is a similar view, partly in section. Fig. 3 is a top plan view of a shaft with a protector applied thereto having a modified fastening means. Fig. 4 is a detail perspective view of the fastening device shown applied in Fig. 3, and Fig. 5 is a view in perspective showing a 45 further modification of the fastening device.

In the drawings, 1 indicates the tubular portion of the guard, which, as shown in Fig. 1, is of elastic material, adapted to fit on a shaft end, said tubular portion terminating in a padded flared end 2. I prefer to use a filling 55 of hair or like durable yielding agent; but I do not wish to be limited in this respect, as it has been found in practice that the hollow end may be inflated to produce the result sought. 60

As shown in Fig. 1, I apply the tubular portion to the shaft, and by reason of the elasticity of the material said tubular portion will engage the surface of the shaft and hold the guard against accidental displacement, 65 although permitting its removal by the user.

As shown in Fig. 3, the tubular portion is slit longitudinally, and the edges of the ends and the edges of the slit are secured over the resilient fastener. The fastener comprises a 70 split ring *a*, having approximately-parallel integral arms *b*, said arms being also connected at their ends by a loop *c*. When this fastening means is applied to the tubular body, the guard will be held against displacement. 75

In Fig. 5 I have shown the tubular portion provided with a split ring *d*, which is secured in the edges of the end, the function of which is to clamp the shaft and hold the guard in place. 80

The construction, operation, and advantages will, it is thought, be understood, and it will be noted in view of the foregoing description that various means for retaining the guard in place may be employed. Furthermore, it will be noted that changes in proportion and other details may be resorted to for successfully carrying the invention into practice without departing from the scope of the claims—as, for instance, the material employed as a casing when the mechanical fastening means are used may be leather, canvas, or other durable substitute. 85 90

Having thus fully described my invention, what I claim as new, and desire to secure by 95 Letters Patent, is—

1. In a guard for vehicle-shafts, a tubular portion terminating in a padded enlargement, and a resilient split ring for securing the tubular portion to the shaft. 100

2. In a guard for vehicle-shafts, a tubular portion terminating in a padded enlargement, and a resilient ring having integral arms.
3. In a guard for vehicle-shafts, a tubular body terminating in a padded enlargement and a resilient split ring having integral arms, said arms being connected by a loop.

In testimony whereof I affix my signature in the presence of two witnesses.

SOUTH G. PRESTON.
